(57) **CLAIM**

The ornamental design for a pole having hoops, as shown and described.

DESCRIPTION

FIG. 1 is a rear perspective view of a first embodiment of a pole having hoops;
FIG. 2 is a first side elevational view thereof;
FIG. 3 is a second side elevational view thereof;
FIG. 4 is a front elevational view thereof;
FIG. 5 is a rear elevational view thereof;
FIG. 6 is a top plan view thereof;
FIG. 7 is a bottom plan view thereof;
FIG. 8 is a rear perspective view of a second embodiment of a pole having hoops;
FIG. 9 is a first side elevational view thereof;
FIG. 10 is a second side elevational view thereof;
FIG. 11 is a front elevational view thereof;
FIG. 12 is a rear elevational view thereof;
FIG. 13 is a top plan view thereof; and,
FIG. 14 is a bottom plan view thereof.

The broken lines shown in the figures show portions of the pole having hoops that form no part of the claimed design.

1 Claim, 12 Drawing Sheets
